United States Patent Office.

B. BLACKSTONE, OF WARREN, ILLINOIS.

Letters Patent No. 96,077, dated October 26, 1869.

IMPROVEMENT IN COMBINED SAW-SET, CLAMP, AND VISE.

The Schedule referred to in these Letters Patent and making part of the same.

To all whom this may concern:

Be it known that I, B. BLACKSTONE, of Warren, in the county of Jo Daviess, and State of Illinois, have invented a new and improved Saw-Set, Clamp, and Vise; and I do hereby declare that the following is a full, clear, and exact description thereof, which will enable others skilled in the art to make and use the same, reference being had to the accompanying drawings, and letters marked thereon, in which—

Figure 1 is a perspective representation of my improved tool.

Figure 2, an elevation of one of the jaws, showing the set, and the means for adjusting it.

Figure 3, a transverse section of that part of the device indicated by the line *w*, fig. 1.

Figure 4, a perspective representation of the saw-set, removed from the jaw of the vise.

The present invention relates to an improved tool, which can be conveniently used as a saw-clamp, saw-set, and vise; and

Its nature consists in the novel manner in which the set is constructed, held in place, and adjusted in the jaw of the vise, in combination with other parts of the device, as the whole is hereinafter fully described.

A A represent stationary standards, which terminate, at their upper ends, in a jaw, J, and have projecting lugs T cast solid to them, for the convenience of fastening the tool to a bench, or other suitable place, in the usual manner.

Curved standards B B are pivoted to the standards A A at C C, and their upper ends terminate in a jaw, K, similarly constructed to the jaw J.

These jaws are operated by a lever, F, and screw D, the latter passing through a cross-piece, G, cast solid to the standards B B, and through a cross-piece, H, cast solid to the standards A A.

A nut, E, countersunk into said cross-piece H, is prevented from being turned around, when the screw D is drawing the jaws of the vise together.

Each of the jaws J K is provided with an auxiliary jaw, as shown at M L', which have projecting lugs L at their end, to receive the screws b, with which the auxiliary jaws are held to the jaws L' M.

The inner face of the jaw L' is so recessed out as to receive a set, P R, whose ends bear against the shoulders formed by means of extending the lugs L through to the inner face of the jaws, as shown at V V, fig. 2.

This set is provided with a series of projections, c e e, &c., which, when the jaws of the vise are shut together, bend over every alternate tooth, or, in other words, set them. A flange, R, projecting out from the part P, supports the saw-teeth during the process of setting.

In making the device, I intend to provide two or more sets, P R, for each vise, numbered to correspond with the number of teeth, per inch, which any ordinary saw may have.

In order to provide room for the set P R to operate properly, the auxiliary jaw M is recessed out at X, the entire length of the jaw J; and to so adjust the set as to give the saw-teeth, shown at d, a greater or less angle, a wedge-shaped gauge, N, is placed between it and the auxiliary jaw L', and it is so arranged that when the set-screws O O, with which it is fastened to the jaw L', are turned to draw the gauge upward, the lower edge of said gauge will be moved toward the jaw M, and consequently give the saw-teeth a greater set.

The operation is very simple, requiring only that the saw-teeth be placed on the flange R, and the jaws closed, by means of lever F.

When the device is used as a saw-clamp or vise, the set P R can be removed.

Having thus fully described my invention,

What I claim, and desire to secure by Letters Patent, is—

The combination of the set R P, provided with projections c e e, &c., with the wedge-shaped gauge N, jaws J K and L' M, and standards A B, as and for the purpose set forth.

B. BLACKSTONE.
